UNITED STATES PATENT OFFICE.

JOSEF GRAFSTEIN, OF NEW YORK, N. Y., ASSIGNOR TO CONJOINT JEWELRY CORPORATIONS INC., OF NEW YORK, N. Y., A CORPORATION OF NEW YORK.

FINGER-RING.

1,228,663.

Specification of Letters Patent.

Patented June 5, 1917.

Application filed June 14, 1916. Serial No. 103,685.

To all whom it may concern:

Be it known that I, JOSEF GRAFSTEIN, a citizen of the United States, and a resident of New York city, in the county of Bronx 5 and State of New York, have invented certain new and useful Improvements in Finger-Rings, of which the following is a specification.

This invention relates to a novel finger 10 ring composed of two complete circles or annular bands, each furnished with a flat inner face and carrying one half of the collet or gem setting. The two halves are soldered face-wise together thus forming the 15 complete ring while the two collet halves become simultaneously fixed opposite each other to form a continuous collet. By my invention, the cuttle bone molds heretofore generally employed for making finger rings, 20 are entirely dispensed with, the construction of the ring is greatly simplified and waste of precious metal is avoided.

In the accompanying drawing:

Figure 1 is a face view of a metal plate; 25 Fig. 2, a face view of the blank stamped therefrom;

Fig. 3, a section on line 3—3 Fig. 2;

Fig. 4, a section through the two ring 30 halves, after being shaped, and before being united;

Fig. 5, a similar section showing such halves united;

Fig. 6, a perspective view of the ring complete;

Fig. 7, a cross section through part of 35 the dies;

Fig. 8, a similar cross section showing the parts in a different position;

Fig. 9, a side view of a ring half showing 40 a modification of the invention;

Fig. 10, a section through the two ring halves before assemblage, and

Fig. 11, a perspective view of the ring complete.

Referring more particularly to Figs. 1—8, 45 the ring is composed of two halves 12, 12, each forming a complete circlet, the two halves being equal in every particular. The cross section of each ring half corresponds 50 to the cross section of the ring to be constructed, taken in planes extending diametrically across the ring. In this way, each half will be furnished with a rounded outer face 13, representing the contour of

the ring moiety and with a flat inner face 55 14. Furthermore, each ring moiety carries one half of the socket 15 that goes to make up the collet or gem-setting.

The two ring halves constructed as described, are soldered together, along their 60 juxtaposed parallel flat faces 14, which thus become entirely concealed, thereby forming a ring 16 of conventional or suitable form and complete in every particular. So also the two semi-circular moieties of the socket 65 or setting are soldered together along their flat parallel mating faces to form a continuous circular setting.

In constructing the ring, I stamp out from a metal plate 17, a flat annulus 18, 70 having an integral flat extension 19 that goes to form one half the setting. The blank is placed between a pair of dies 20, 21 (Fig. 7) of which the lower die 20 constitutes the matrix, while the upper die 21 75 is flat.

The cross section of the matrix, corresponds to the cross section of the ring half to be struck up, it being therefore provided with a rounded face 22, corresponding to 80 80 the contour 13. So also the matrix is furnished with a depression adapted to shape one half of the collet, this part of the matrix being not illustrated. When the metal is forced by the flat upper die 21, into the 85 matrix 20 (Fig. 8), a completely shaped ring half 12 will be produced, the upper side 14 of such ring half being flat, owing to the flat working face of die 21.

The two ring halves died as described, 90 are soldered together along their flat faces 14, sidewise of each other, by which operation, the two setting halves 15 will become fixed in their proper or opposed positions, thus forming a complete or continuous setting. This setting is furnished with prongs 95 23, to form a complete or continuous collet. The ring assembled in the manner described, is polished, which completes the operation.

In Figs. 9—11, the prong-setting of Fig. 100 6 is replaced by a box-setting. Here the matrix that shapes the ring half 24 is formed with the outline of a lace or other pattern, which outline is thus molded into the setting as at 25 Fig. 9. The pattern is then 105 sawed out, and the two ring halves as well as the two box halves are soldered together, thus forming a complete ring 26 furnished

with an open work pattern 27 in its setting. Finally, an annular plate 28 is fitted into the top of the box for retaining the gem. With this embodiment therefore, the box 25 5 constitutes the setting 15 of Figs. 4-6, while the prongs 23 are omitted.

I claim:

1. A finger ring comprising a first annular ring half, a first socket half carried thereby, 10 said socket half being semi-circular in cross section, a second annular ring half, a second socket half carried thereby and likewise semi-circular in cross section, the inner faces of the two ring halves contacting with each 15 other, and the inner faces of the two socket halves being parallel and likewise contacting with each other, to form a continuous circular socket, the two ring halves as well

as the two socket halves being soldered to each other.

2. A finger ring comprising a first annular ring half, a first socket half carried thereby, 20 said socket half being semi-circular in cross section, prongs projecting from the socket half, a second annular ring half, a second 25 socket half carried thereby and likewise semi-circular in cross section, prongs projecting from the last named socket half, the inner faces of the two ring halves contacting with each other, and the inner faces of the two socket halves being parallel and likewise 30 contacting with each other to form a continuous circular socket, the two ring halves as well as the two socket halves being soldered to each other.

JOSEF GRAFSTEIN.
